UNITED STATES PATENT OFFICE.

HERBERT LOUTH, OF PITTSBURGH, PENNSYLVANIA, ASSIGNOR TO WESTINGHOUSE ELECTRIC & MANUFACTURING COMPANY, A CORPORATION OF PENNSYLVANIA.

SAFETY DEVICE FOR LAUNDRY MACHINES.

Application filed June 17, 1924. Serial No. 720,499.

My invention relates to improvements in laundry machines and more particularly to interlocks for foldable wringers of the type generally used with foldable washing machines.

The object of the invention, generally stated, is the provision of a foldable wringer interlock that shall be simple and efficient in operation and be readily and economically manufactured.

A more specific object of the invention is to effect the retaining of the driving motor of a washing machine inoperative when the wringer is in its folded position, and the wringer in its operative position when the motor is in operation.

It is also an object of this invention to provide for the stopping of the driving motor of a washing machine through the releasing of the wringer lock.

Other objects of the invention will, in part, be obvious and in part appear herein-after.

The invention, accordingly, is disclosed in the embodiment hereof shown in the accompanying drawing, and comprises the features of construction, combination of elements and arrangement of parts which will be exemplified in the construction herein-after set forth and the scope of the application of which will be indicated in the claims.

For a fuller understanding of the nature and objects of the invention, reference should be had to the following detailed description taken in connection with the accompanying drawing, in which:

Fig. 1 is a side elevation of a washing machine, parts being broken away to show an interlock in accordance with this invention.

Fig. 2 is a side elevation of the interlock showing it mounted on a washing machine.

Fig. 3 is a front elevation of the interlock, parts being broken away to show its construction, and

Fig. 4 is a detail of the operating handle of the interlock.

Referring now to the drawing, 13 designates, generally, a washing machine provided with an oscillatory tub and a foldable wringer. In this construction, both the tub 14 and the wringer 10 are disposed to swing about horizontal axes. As shown, the wringer 10 is mounted on a shaft 11 journaled in a housing 16, carried by a post 12 attached to

the washing-machine frame and, when folded, lies in a horizontal plane above the tub, as indicated by dotted lines in Fig. 1. In order to give rigidity to the wringer when set in its different positions, the housing 16 is formed to present a bearing face to receive the bearing flange 17 of the wringer. Since the object of providing a foldable wringer is to obtain compactness, it follows that the wringer must be so mounted that, when folded, it lies very close to the tub. Consequently, when the wringer is in or moved to its folded position, if the tub, which is operated by the driving motor 15, is in motion or is set in motion, damage to the parts will result.

With a view to avoiding possible destruction of the parts of the washing machine, a safety device or interlock is provided which prevents the operator from starting the driving motor when the wringer is in its folded position, or from moving the wringer into its folded position when the motor is in operation.

As shown in Fig. 3, a motor control is provided which includes a switch 18 connected in the motor circuit in the usual manner, and a slide 19 mounted on the switch casing in alignment with the switch lever 20. By mounting the switch 18 so that, when the motor circuit is completed, the lever is in its upper position, as shown in Fig. 3, the stopping of the motor may be effected by thrusting the slide 19 downward. In order to release the lever 20 so that it may be operated to complete the motor circuit, a spring 21 is interposed between the switch casing and the upper portion of the slide 19. It will be readily understood that this spring is compressed as the slide is moved downward and that it will expand to project the slide upward as soon as the pressure thereon is released.

The slide 19 is provided with a centrally-disposed slot 19a through which a guide pin 19b extends to restrict the movements of the slide in its vertical path.

The wringer is locked in its operative position by a bolt 25 revolvably and slidably mounted in bearings carried by the housing 16. These bearings may be formed in the housing 16 or in members carried by the housing, and, in this particular construction, are formed in the end walls of an auxiliary housing 22 cast integral with the main hous-

ing 16. In order that the bolt 25, which is disposed to slide parallel to the axis of the shaft 11, may engage positively the wringer to retain it in its operative position, an opening is drilled in the wringer flange 17 and located to aline with the bolt 25 when the wringer has been raised to its erect or working position. The operation of the bolt is effected by means of a handle 26 pinned to its outer end.

Since it is desired to prevent the releasing of the wringer when the motor is in operation, a bolt stop is provided which cooperates with the bolt handle to retain the bolt against longitudinal movement until it has been set in a predetermined position where a notch 28, provided in the handle, alines with the stop. In order to effect the stopping of the motor through the setting of the handle to permit longitudinal movement of the bolt, a rack-and-pinion mechanism is interposed between the bolt and motor control. As will be observed by reference to Fig. 3, the rack-and-pinion mechanism includes a pinion 24 fixed to the bolt 25 and meshing with a rack 23 slidably mounted in the housing 22.

Since it is desired to effect the operation of the switch 18 as the bolt is set for longitudinal movement, the rack 23 is disposed in alinement with the slide 19 and is so positioned that, when the handle is operated to aline the notch 28 with the stop 27, it is projected to the limit of its downward movement, forcing the slide 19 downward. It is further to be noted that the pinion is so positioned on the bolt that, as the latter is moved longitudinally to release the wringer, the pinion engages the wall of the housing 22 at the limit of the desired movement of the bolt and while the handle is still positioned over the stop 27. Thus, the bolt is held against rotation and the slide 19 is locked in its lowermost position, where it prevents the manual operation of the switch. Further, the wringer flange or plate 17 prevents movement of the bolt to the right, as viewed in Fig. 3, as long as the wringer remains in its folded position. In order to facilitate the mounting of the bolt, pinion and rack, the housing is provided with a door 29 that may be mounted to swing about either a vertical or a horizontal axis.

In describing the operation of the interlock, it may be assumed that the washing machine is brought from the store room, with the wringer in its folded position and the switch locked against manual operation. To prepare the machine for use, the wringer is raised to its erect or operating position, alining the bolt-receiving opening with the bolt. In order to maintain the wringer in its operative position, the bolt 25 is moved to the right, positively engaging the wringer, as shown in Fig. 3. The handle 26 is now out of engagement with the stop 27 and is

rotated counter-clockwise, as viewed in Fig. 2, operating the pinion 24 and raising the rack 23. Thus, the slide 19 is released and the spring 21 projects it upward out of engagement with the switch lever 20. As soon as the switch lever is released, it may be manually operated to throw it into its "on" or its "off" position, starting or stopping the motor at will.

When it is desired to return the wringer to its folded position, the bolt 25 must be withdrawn to permit the wringer to be rotated about its axis. In order to withdraw the bolt 25, the handle 26 must be set so that the notch 28 alines with the stop 27. In setting the handle to permit longitudinal movement of the bolt 25, it must be rotated clockwise, as viewed in Fig. 2, thereby effecting the rotation of the bolt 25. As the bolt 25 is rotated, the rack-and-pinion mechanism is operated, projecting the slide 19 downward, operating the switch lever 20 to break the motor circuit. Thus, in operating the locking mechanism to release the wringer, the motor control is operated to stop the motor. When the bolt 25 occupies its extreme left-hand position, the slot 28 fits over the stop 27 and thus locks the switch in open position. Accordingly, the wringer cannot be thrown into its folded position without first stopping the motor. Further, when the bolt 25 has been withdrawn to release the wringer, the bolt handle 26 is locked in engagement with the stop 27, thus making it impossible to set the motor in operation until the wringer has been raised to its operative position and the bolt projected into its locking position.

Since certain changes may be made in the above construction and different embodiments of the invention may be made without departing from the scope thereof, it is intended that all matter contained in the above description or shown in the accompanying drawing shall be interpreted as illustrative, and not in a limited sense.

I claim as my invention:

1. In a washing machine, in combination, a foldable wringer, a driving motor for the wringer, a switch for the motor, and inter-dependent means for locking the wringer in a predetermined position and for controlling the operation of the switch.

2. In a washing machine provided with a driving motor and a foldable wringer, the combination of a motor control, a locking member disposed to lock the wringer in operative position, means actuated by said locking member to operate the motor control, and means for retaining the locking member in its locking position when the motor is in operation.

3. In a washing machine provided with a driving motor and a foldable wringer, the combination of a motor control, a locking

- member disposed to lock the wringer in operative position, means actuated by said locking member to operate the motor control, and means for retaining the locking member 5 in its locking position when the motor is in operation, said locking-member retaining means being adapted to permit the unlocking of the wringer when the motor control has been operated to stop the motor.
- 10 4. In a washing machine provided with a driving motor and a foldable wringer, the combination of a bolt provided with an operating handle disposed to engage the wringer to lock it in an operative position, 15 a motor control operable by said bolt, a bolt stop cooperative with said bolt-operating handle to retain the bolt in its locking position when the motor is in operation and to permit the withdrawal of the bolt when the 20 motor control has been operated to stop the motor.
5. In a washing machine provided with a driving motor and a foldable wringer, the combination of a bolt provided with an operating handle disposed to engage the wringer to lock it in operative position, a motor control operable by said bolt to stop the motor, a bolt stop cooperative with said bolt-operating handle to retain the bolt in its 25 locking position when the motor is in operation and to permit withdrawal of the bolt when the motor control has been operated to stop the motor.
6. In a washing machine provided with a 30 driving motor and a foldable wringer, the combination of a bolt disposed for rotary and longitudinal movement and adapted to engage the wringer to lock it in operative position, said bolt being provided with an operating handle, a motor control, means operable upon the rotation of the bolt to actuate the motor control, a bolt stop cooperative with said handle to retain the bolt in engagement with the wringer when the motor 35 is in operation.
7. In a washing machine provided with a driving motor and a foldable wringer, the combination of a bolt disposed for rotary and longitudinal movement adapted to engage the wringer to lock it in operative position, said bolt being provided with an operating handle, a motor control, means operable upon the rotation of the bolt to actuate the motor control, a bolt stop cooperative 40
- 50
- with said handle to retain the bolt in engagement with the wringer when the motor is in operation, said handle being notched to permit movement over the bolt stop when the motor control has been operated to stop the motor, thereby releasing the wringer. 55
8. In a washing machine provided with a driving motor and a foldable wringer, the combination of a bolt disposed for rotary and longitudinal movement adapted to engage the wringer to lock it in operative position, said bolt being provided with an operating handle, a motor control, a rack-and-pinion mechanism operated by the rotation of the bolt and cooperative to effect the operation of the motor control, a bolt stop positioned to engage the handle to prevent the releasing of the wringer when the motor is in operation, said handle being notched to permit movement over the stop when the motor control has been operated to stop the 60 70 75 motor. 65
9. In a washing machine provided with a driving motor and a foldable wringer, the combination of a locking member disposed for longitudinal and rotary motion and adapted to engage the wringer, said wringer being provided with an opening for the reception of the locking member, a stop cooperative with said locking member to retain it in engagement with the wringer when the 80 motor is in operation, said locking member being adapted for movement transversely of the stop when the motor has been stopped, and means operable by said locking member to effect the operation of said motor control. 85
10. In a washing machine provided with a driving motor and a foldable wringer, an interlock comprising a locking member disposed to engage the wringer, a motor control operable by the locking member, means cooperative to retain the locking member in engagement with the wringer when the motor control is in its on position, said retaining means being adapted to prevent the 90 operation of the locking member when the wringer is moved from its erect position, thereby to retain the motor control in its off position. 95
- In testimony whereof, I have hereunto subscribed my name this 6th day of June 100 1924.

HERBERT LOUTH.
